ATTORNEY

UNITED STATES PATENT OFFICE.

MAY THOMAS HORN, OF JERSEY CITY, NEW JERSEY.

RESERVOIR-FOUNTAIN-PEN FILLER.

SPECIFICATION forming part of Letters Patent No. 722,508, dated March 10, 1903.

Application filed August 12, 1902. Serial No. 119,380. (No model.)

To all whom it may concern:

Be it known that I, MAY THOMAS HORN, a citizen of the United States, residing at Jersey City, county of Hudson, State of New Jersey, have invented certain new and useful Improvements in Reservoir-Fountain-Pen Fillers, of which the following is a specification.

My invention relates to means for safely containing ink in quantity and for delivering it to the reservoir of fountain-pens in a cleanly manner by the compression of the body of the filler.

In order that those skilled in the art to which my invention appertains may understand, construct, and use my invention, I will proceed to describe it, referring to the drawings herewith, in which—

Figure 1 is a longitudinal central section of one form of my invention. Fig. 2 is a top view of Fig. 1. Fig. 3 is another form of my invention in longitudinal central section on line x y of 4; and Fig. 4 is an end view of Fig. 3 looking from the bottom end upward to show the round upper end and wedge-shaped lower end of the reservoir A, the sides being pinched together at the bottom and held by a clip K. Fig. 5 is another form of my invention shown in longitudinal central section; and Fig. 6 is a top view of same, showing the discharge or filling cone solid with the reservoir and the open lower end of the reservoir A closed by a screw-cap G. All these forms are refillable and compressible.

In all the figures the same reference-letters indicate like or equivalent parts.

A is the ink-reservoir.

B is the threaded head-piece, conical in form at its upper end and at its top coming to a fine point for a purpose disclosed farther on in this specification.

C is a screw-cap having packing I in its upper end and screwed upon head-piece B at E to seal the apparatus.

D is a fine hole running longitudinally through the head-piece B, through which the ink is to be discharged in a minute stream for filling a fountain-pen. The conical sides or surfaces of the head-piece B approach at its top closely to the edges of the fine hole D, so that the top of the cone is practically merely a needle-point at J.

Head-pieces B in Figs. 1 and 3 are screwed into the upper end of reservoir A at F, so that the said reservoir can be refilled by removing the head-piece B and closed again by 55 replacing it. In Fig. 5 the lower end of the reservoir A is opened for refilling and again closed by removing the cap G and again replacing it by screwing it onto reservoir A at screw H. In Figs. 1 and 5 the reservoir A is 60 shown as cylindrical, while in Fig. 3 it is cylindrical at its upper end and wedge-shaped at its bottom, the sides being held together tightly by a clip K.

The effect of making the top of the cone on 65 head-piece B a fine point is that the drop of ink which will remain upon the point J or upper end of the fine hole D will not run down the sides of the cone, but will be held fixed at the said point a period and be drawn again 70 into the reservoir A through hole D by the inrush of air which occurs after the discharge of ink from it.

The reservoir A is to be made of celluloid or equivalent material, which has a slight 75 flexibility and resiliency, so that to discharge ink from the reservoir a pressure by the fingers upon its outer surface causes the sides to yield inwardly and the ink to flow outwardly when cap C is removed and the apparatus is turned upon its side to fill a pen. Upon removing the pressure the sides return to their original form and air is sucked into the reservoir to supply the place of the discharged ink, so that this operation may be 80 repeated until all the ink is discharged. To refill, the head B or the cap G is removed, respectively.

I am not aware that reservoirs for ink have ever been made of material having the qualities of celluloid, as above set forth.

Having now fully described my invention and the manner in which I have embodied it, what I claim as new and as my invention, and desire to secure by Letters Patent, is— 95

As an article of manufacture, an ink-reservoir and fountain-pen filler consisting of an ink-chamber A of flexible material as celluloid; a conical head-piece B having a longitudinal central perforation D of minute size, 100 and threaded to receive a closing cap C and packing I, said ink-chamber A being con-

structed as shown and described with a threaded end to receive a threaded closing-piece, whereby the chamber A may be opened for refilling and closed to retain ink, substantially
5 as specified.

In testimony whereof I have signed my name to this specification, in the presence of

two subscribing witnesses, this 8th day of August, 1902.

MAY THOMAS HORN.
